UNITED STATES PATENT OFFICE.

EUGENE S. DEVLIN, OF NEW YORK, N. Y.

DESIGN FOR A PEN AND PENCIL HOLDER.

SPECIFICATION forming part of Design No. 34,478, dated May 7, 1901.

Application filed April 2, 1901. Serial No. 54,095. Term of patent 7 years.

To all whom it may concern:

Be it known that I, EUGENE S. DEVLIN, a citizen of the United States, and a resident of the city of New York, (Port Richmond, borough of Richmond,) in the county of Richmond and State of New York, have invented and produced a new and original Design for a Pen and Pencil Holder, of which the following is a specification, reference being had to the accompanying drawing, forming a part thereof, in which is represented a plan view of a pen and pencil holder embodying the features of my design.

The leading feature of the design consists in an open-ring body A, the terminals B of which ring-body cross one another and are bowed in opposite directions, the members C thus bowed being separated, inclosing an approximately oval space.

The minor feature of the design consists in carrying the free ends of the oppositely-curved members C loosely across one another and shaping the terminals D of such members in such manner that they are straight and face in opposite directions.

Having thus described my invention, I claim as new and desire to secure by Letters Patent—

The design for a pen and pencil holder as herein shown and described.

In testimony whereof I have signed my name to this specification in the presence of two subscribing witnesses.

EUGENE S. DEVLIN.
